AUGUST SUNDH, OF HASTINGS-UPON-HUDSON, NEW YORK.

BLOCK FOR STRIP-BLOCKING MACHINES.

1,259,163.

Specification of Letters Patent. Patented Mar. 12, 1918.

Application filed March 25, 1916. Serial No. 86,694.

To all whom it may concern:

Be it known that I, AUGUST SUNDH, a citizen of the United States, residing in Hastings-upon-Hudson, in the county of 5 Westchester and State of New York, have invented a new and useful Improvement in Blocks for Strip-Blocking Machines, of which the following is a specification.

My invention relates to an improvement 10 in blocks for strip blocking machines.

With the blocks now used in blocking strip metal, the roll of metal after being blocked has to be unwound before it can be taken away from the block, as owing to the 15 tension on the strip as it is being blocked, it will be coiled very tightly on the block. This consumes time of course, and is troublesome. I have provided a block, however, which is collapsible, that is to say, after the strip has 20 been blocked, the block may be collapsed and the strip easily removed. My block when expanded ready to receive the strip for blocking, has a smooth cylindrical and unbroken surface for the strip to be wound 25 on, which is a great advantage over the expansion blocks now in use, in which the block after being expanded has openings in its periphery due to the expansion of the block, and the metal, especially the very thin 30 metal in the blocking process is forced into these openings, which leaves ridges on the metal and sometimes even the metal is cut by being forced into these openings. Another advantage of the present block is that 35 only part of its periphery is collapsed after the strip has been blocked, the strip being left supported on the part not collapsed, which provides convenient means for grasping the strip to remove it.

40 In the accompanying drawings illustrating my invention, Figure 1 is a sectional elevation view of the block, as it appears ready to receive the strip to be blocked; Fig. 2 is a sectional view of the block taken on the line A—A of Fig. 1, but with the block collapsed; Fig. 3 is a view on the line B—B of Fig. 1; Fig. 4 is a section on the line C—C of Fig. 1; and Fig. 5 is a section on the line E—E of Fig. 1.

50 The block which is cylindrical in shape, is formed in sections, part of these sections being collapsible and the rest fixed; the fixed sections, which I have designated 1 on the drawings, and are three in number, extend longitudinally of the block for its entire 55 length, these sections being T-shaped in

cross section, their outer surfaces or periphery being convex. These sections are held in place permanently by caps 2 at each end of the block, the ends of the sections fitting in 60 grooves in these caps and resting on springs 3. A hollow shaft 4 extends longitudinally of the block for its entire length, being threaded into the cap 2 at the left hand end of the block as viewed in Fig. 1. This shaft 65 4 has a bearing in bearings 5 and it is through this shaft that the block is rotated through any convenient medium, such as a pulley on the shaft driven by a belt from a motor, or by gearing direct. Within the 70 shaft is a solid shaft 6, this shaft being screw threaded at its left hand end as viewed in Fig. 1, and being provided for the purpose of operating the collapsible or movable sections of the block. These sections, designated 7, extend longitudinally of the block for its entire length, and as shown in Figs. 2 and 3, are movable to and from the center or longitudinal axis of the block in grooves or slots in the caps 2, and when moved out they 80 entirely fill up the spaces between the fixed sections 1. Thus when these sections 7 are moved to their extreme outward position, the periphery of the entire block will be smooth and unbroken. To operate these sections 85 tongues 8 are formed on their inner side, these tongues entering openings 9 cut through the hollow shaft 4. Shoulders 10 formed on the inner shaft 6 engage these tongues to hold the sections 7 in their extreme outward position. As before noted, the shaft 6 is screw threaded at its left hand end, and a hand wheel 11 is screwed thereon, this hand wheel being held in place on the shaft by a cap 12 secured to the cap 2. A 90 squared portion 13 is formed about midway of the length of the shaft, this squared portion entering a bushing 14 within the shaft 4, the bushing being secured to the latter by means of a small set screw 15. Thus it will 100 be seen that by rotating the hand wheel 11, the shaft 6 will be caused to travel longitudinally either to the left or right, being held against rotation by the bushing 14 and squared portion 13 of the shaft. Now to 105 permit and cause the portions 7 to move in toward the longitudinal axis of the block, the hand wheel 11 is turned in the proper direction to cause the shaft 6 to travel to the left, Fig. 1. The shoulders 10 will travel 110 off the tongues 8 of the sections 7, and so soon as they ride off these tongues, the sec-

tions 7 are free to be forced inwardly by springs 16 which are placed at each end of each section and between the ends of the sections and the cap 2. Now to move the sections outwardly again, the hand wheel 5 is turned in the opposite direction, and the beveled front end of the shoulders 10 will strike the beveled or cut away back part of the tongues 8 on the movable sections, and 10 gradually force the sections outwardly until the straight face of the shoulders rides on the straight face of the tongues 8, at which time the sections 7 will be in their extreme outward position and held there. In this 15 position, it will be seen that the contour of the block is circular, and that its periphery is smooth and unbroken. After the strip has been blocked, the sections 7 are moved inwardly again, and the blocked strip left 20 hanging on the sections 1, but as these sections are spaced apart, the strip may be easily grasped, and as these sections are slightly yieldable by reason of resting on the springs 3, it will be seen that it is an 25 easy matter and requires but a moment to remove the strip, by simply pulling it off the section 1 instead of having to unwind it off the block as has had to be done with the type of block in use at the present time.

30 It will be readily seen that my block presents many advantages over the other blocks in the art of strip blocking, and that I have provided a block which is simple in construction, and operation, and which by reason 35 of its simple construction will not easily get out of order.

I do not desire to be limited to the precise details and arrangement of parts herein disclosed as others skilled in this art might 40 make various changes therein without departing from the spirit and scope of the invention.

What I claim is:—

1. In a block adapted to wind a strip coming from a strip mill, the combination of a plurality of sections, inclined surfaces on said sections, manually controlled mechanism with inclined surfaces coacting with the inclined surfaces of said sections where- 45 by the sections are expanded or collapsed by the operation of said manually operated means, and yieldingly supported ribs between the sections.
2. In a block adapted to wind a strip com-

ing from a strip mill, the combination of a 55 plurality of sections forming part of the winding surface of the block, and yieldably supported ribs between said sections and co-acting therewith to make the winding surface of the block smooth and unbroken. 60

3. In a block adapted to wind a strip coming from a strip mill, the combination of a plurality of movable sections, guiding means for said sections, and a plurality of yieldably supported ribs coöperating with said 65 movable sections, to form the block, and guiding means for said ribs.

4. In a block adapted to wind a strip coming from a strip mill, the combination of a plurality of spaced apart movable sections, and a plurality of yieldably supported T 70 ribs to fill up the space between said sections, said sections and T-ribs coöperating to form a smooth unbroken winding surface for the block.

5. In a block adapted to wind a strip fed from a strip mill, the combination of a hollow shaft, a shaft within said hollow shaft, a plurality of sections surrounding said shafts and forming part of the winding surface of the block, said inner shaft adapted to be actuated to impart bodily movement to said sections, means to prevent relative rotation of the two shafts, and yieldingly supported members between the said sections, the said sections and yieldingly supported members together forming the winding surface of the block. 80

6. In a block adapted to wind a strip fed from a strip mill, the combination of a hollow shaft, a shaft within said hollow shaft and movable longitudinally thereof, a plurality of sections surrounding said shafts and forming part of the winding surface of the block, the inner shaft adapted to be actuated to impart bodily movement to said sections, means to prevent relative rotation of the two shafts, and yieldingly supported members between said sections, said members and sections together forming the winding surface of the block. 90

In testimony whereof I have signed my name to this specification in the presence of two subscribing witnesses.

AUGUST SUNDH.
